UNITED STATES PATENT OFFICE.

JAMES WM. DEARING, OF BROOKLYN, NEW YORK.

DESIGN FOR A BURNER FOR LANTERNS.

SPECIFICATION forming part of Design No. 28,100, dated December 28, 1897.

Application filed November 2, 1897. Serial No. 657,210. Term of patent 7 years.

To all whom it may concern:

Be it known that I, JAMES WM. DEARING, a citizen of the United States, residing at Brooklyn, in the county of Kings and State 5 of New York, have invented and produced a new and original Design for a Burner for Lanterns, of which the following is a specification, reference being had to the accompanying drawing, forming a part of this specification, in which is shown a perspective view 10 of a lantern-burner embodying the features of my design.

The design consists in a base A and in arms C, which extend upward from the base, the 15 base surrounding a burner-tube B.

The design further consists in the T shape of the arms C, whereby each arm is provided with a head D, and in the serrations E, which appear in the upper edges of the head portion of the arms C.

2c

I claim—

The design for a burner for lanterns herein shown and described.

JAMES WM. DEARING.
